COOKING STOVE.

No. 16,930.

Patented Oct. 12, 1886.

UNITED STATES PATENT OFFICE.

JAMES W. DWYER, OF ST. LOUIS, MISSOURI.

DESIGN FOR A COOKING-STOVE.

SPECIFICATION forming part of Design No. 16,930, dated October 12, 1886.

Application filed June 14, 1886. Serial No. 205,147. Term of patent 7 years.

To all whom it may concern:

Be it known that I, JAMES W. DWYER, of the city of St. Louis, Missouri, have invented and produced a new and original Design for 5 Cooking-Stoves, of which the following is a specification, reference being had to the annexed drawing, making part of this specification, and exhibiting the newly-designed stove in perspective.

10 The characteristics of this design are as follows: the flowery ornamentation *a*, appearing upon the fire-place door *A*; the oven-shelf *B*, having the row *b* of T-shaped slots, the alternate slots being arranged in opposite directions, and the row terminating at both ends with a curved slot, *b'*; the flowery ornamentations *c*, *c'*, *c''*, and *c'''*, upon the oven door *C*, at its four corners, respectively, also the escutcheon *c'* upon the oven-door; the escutcheon at its top is semicircular, and below the semicircular portion, at each side, the edge of the escutcheon curves first inwardly and then outwardly, and ultimately forming a rounded corner at the bottom of the escutcheon, and 25 between the corners the lower edge of the escutcheon is straight, and upon the escutcheon appears the figure of the sun rising from the ocean; the flowery ornamentation *d* upon the hot-closet door *D*; the flowery ornamentation *e* upon the convex base *E* of the stove; the flowery ornamentation *f* upon the upper part 30 of the stove-legs *F*, the leg below the ornamentation having a smooth finish and terminating in the rounded knob *f'*.

I claim...
